UNITED STATES PATENT OFFICE.

DAVID L. WINEBERG, OF ROCKLAND, MASSACHUSETTS, ASSIGNOR TO UNITED SHOE MACHINERY COMPANY, OF PATERSON, NEW JERSEY, A CORPORATION OF NEW JERSEY.

END-LASTING MECHANISM.

1,027,024.

Specification of Letters Patent.

Patented May 21, 1912.

Application filed July 25, 1910. Serial No. 573,687.

To all whom it may concern:

Be it known that I, DAVID L. WINEBERG, a citizen of the United States, residing at Rockland, in the county of Plymouth and 5 State of Massachusetts, have invented certain Improvements in End-Lasting Mechanisms, of which the following description, in connection with the accompanying drawings, is a specification, like reference characters on the drawings indicating like parts in the several figures.

This invention relates to end lasting apparatus and particularly to devices adapted to be used in coöperation with end embracing wipers in stretching an upper over a last. These devices which are used in place of the workman's fingers to hold the upper upon the wipers are called "retarders" because their function is to retard the slipping 15 of the upper over the moving wipers. In their use the marginal portion of the upper is spread over the wiper plates, which have an advancing and inwardly closing movement and usually also an upward 20 movement relatively to the last, and clamped down thereon by the retarder.

An object of this invention is to provide a simple, light and very effective retarder which can be readily moved from an out-of-30 the-way position to working relation to the shoe and by which an upper clamping pressure that is easily controlled and varied can be applied to the upper at the sides and end of the toe.

It is also an object to provide a retarder which offers a minimum of obstruction to the operator's view of the work.

An important feature of this invention is found in a retarder which comprises a bar 40 movably supported in front of the shoe and having a handled end extending over the shoe and a depending foot to clamp the upper against the wipers and regulate the freedom with which the upper slips over the 45 wipers as they are advanced and closed.

It is also a feature of this invention that the bar is connected to its support to permit it to have movement lengthwise of the shoe in the direction of the advance of the wipers 50 and under control of the operator.

The clamping foot is herein shown as a crescent-shaped plate of rigid construction which is adapted to engage the upper at the end and for a distance on each side of

the toe, particularly at the "corners" of the toe. In use the retarder may be allowed to advance with the wipers while its side portions restrain the slippage of the upper over the inwardly closing wipers to effect a maximum straining of the upper at the corners 60 of the toe. This is desirable for the reason that in the pulling-over operation as practised by the commercial pulling-over machine the upper is tightly drawn to the last at the end and at opposite sides of the ball 65 but it is not directly strained at the corners of the toe.

It is also a feature of the invention to make provision for lateral movement of the retarder during the closing of the wipers 70 whereby greater upper pulling force can be applied at one side of the toe than at the other side.

These and other features of this invention will more fully appear from the following 75 description of a preferred embodiment thereof and will then be pointed out in the claims.

The drawing shows a toe lasting mechanism equipped with this invention. 80

The wipers 2 are supported and guided in the carrier 4 and are actuated by usual connections with a hand lever 5 to advance longitudinally of the shoe and simultaneously to close inwardly from opposite sides 85 of the toe whereby to lay the upper over the margin of the sole. In these respects the lasting mechanism may be similar to that shown in the Grandy Patent No. 521,954, or it may be of any other wiper type. Erected 90 upon the wiper support 4, as from a detachable base plate 10 is a post 12 the stem of which is embraced by the longitudinally slotted end of a lever 15 which is adapted to extend rearwardly over the shoe as shown 95 in the drawing and to be turned laterally to an out-of-the-way position when not required for use. The rear end of the lever is formed as a handle and from the lever depends a crescent-shaped foot adapted to 100 clamp the upper of the end and sides of the toe down upon the top face of the wiper plates 2. When downward pressure is applied upon the handle the lever fulcrums on the head of the post 12 and the foot retards 105 the slipping of the upper over the wipers as they are advanced and closed. The slot by which the stem 12 is embraced allows the

retarder to accompany the wipers in their advance to a greater or less extent determined by the operator through his engagement with the handle end of the lever. The 5 rearwardly extending arms of the clamping foot are unable to partake of the closing movement of the wiper plates and therefore the retarder serves to delay or retard the slipping of the upper of the sides of the toe 10 more than it does the upper of the end of the toe and so causes a relatively greater stretching of the upper over the sides or corners of the toe portion of the last. The clamping foot is preferably connected rigidly to the lever and the slotted end of the lever is fitted to the stem 12 loosely enough to enable the operator by his grasp on the handle to roll the retarder slightly as may be found desirable to increase the grip of 15 20 the upper on either side of a toe which may require special pulling.

Having explained the nature of this invention and described a preferred construction embodying the same, I claim as new 25 and desire to secure by Letters Patent of the United States:

1. A retarder for bed lasting machines comprising a bar extending lengthwise of a shoe which occupies position to be lasted in 30 the machine and pivotally supported in front of the shoe and having a handle on its rear end, said bar having a depending foot adapted to be held in clamping engagement with the marginal portion of the upper 35 upon the lasting plates by pressure applied to the handle transversely of the length of the handle.

2. A retarder for bed lasting machines comprising a lever extending lengthwise of 40 the shoe which occupies position to be lasted in the machine, said lever being fulcrumed in front of the shoe and having its operating end extended rearwardly over the shoe to form a handle, a depending stem on the 45 lever between the pivot and the handle and a crescent-shaped foot on the stem and located to clamp the upper against the lasting plates.

3. A retarder for lasting machines comprising a support, a lever fulcrumed on the 50 support in front of the shoe and having a handle extending rearwardly over the shoe, a crescent shaped clamping foot on the lever having its concave edge toward the last and 55 adapted to extend down in front of the last below the plane of the last bottom, and connections permitting relative movement between the foot and the support in a direction longitudinal of the lever.

60 4. In an end lasting mechanism the combination with end embracing wipers and supporting and operating means therefor, of a retarder comprising a lever arranged longitudinally of the shoe and having a pin 65 and slot pivotal connection with the wiper

support and a rear end formed as a handle extending over the shoe, and a crescent-shaped foot depending from the lever to clamp the upper upon the wipers, said pin and slot connection permitting movement of 70 the retarder lengthwise of the shoe with the wipers.

5. A retarder for bed lasting machines comprising a carrier extending lengthwise of a shoe which occupies position to be lasted in the machine, said carrier being movably supported in front of the shoe and provided with a handle on its rear end and having a depending foot shaped to clamp the upper at the two sides of the toe and 80 having means by which to effect lateral manipulation for relatively varying the action of the retarder at the two sides of the toe.

6. In an end lasting mechanism, the combination with toe embracing wipers and supporting and actuating mechanism therefor including means for advancing and closing the wipers, of a retarder formed to clamp the upper against the wipers at the end and sides of the toe and having a sliding connection with the wiper supporting mechanism to permit it to have movement lengthwise of 85 the shoe with the advancing wipers.

7. In an end lasting mechanism, the combination with toe embracing wipers and supporting and actuating mechanism therefor including means for lifting the wipers from a starting position below the plane of the last bottom to stretch the upper upwardly and means for advancing and closing the 100 wipers, of a retarder having a crescent shaped foot formed to extend down around the toe of the last to clamp the upper against the depressed wipers at the end and sides of the toe and mounted to permit, under control of the operator, a rising movement with the wipers and an advance movement with the advance of the wipers while resisting inward movement of the upper from the corners of the toe with the closing of the wipers.

8. In an end lasting mechanism, the combination with toe embracing wipers and supporting and actuating mechanism therefor including means for advancing and closing the wipers, of a retarder formed to clamp the upper against the wipers at the end and at the sides of the toe and slidably supported on said mechanism to permit it to accompany the advance movement of the wipers while detaining the edge of the upper at the corners of the toe from inward movement with the closing wipers.

9. In an end lasting mechanism, the combination with toe embracing wipers and supporting and actuating mechanism therefor including means for advancing and closing the wipers, of a retarder formed to clamp the upper against the wipers at the end and at the sides of the toe and constructed and arranged to effect, in coöperation with said 125 130

movements of the wipers, a greater stretching of the upper over the corners of the toe than over the end of the toe.

10. In an end lasting mechanism the combination with toe embracing wipers and supporting and actuating mechanism therefor which is movable upwardly and downwardly and includes means for advancing and closing the wipers, of a retarder formed 10 to enable it to be used to clamp the upper against the wipers at the end and sides of the toe while the wipers are a substantial distance below the plane of the last bottom and mounted to accompany the wipers in 15 one only of said wiper movements as and for the purpose described.
11. In an end lasting mechanism the combination with toe embracing wipers and supporting and actuating mechanism therefor 20 including means for advancing and closing the wipers, of a retarder formed to clamp the upper against the wipers at the two sides of the toe and having a handle extending lengthwise of the shoe by which lateral 25 movement can be effected during the closing of the wipers to cause greater straining of the upper at one side of the toe than at the other side.

12. An end lasting machine having, in 30 combination, toe embracing wipers and

means for operating them, and a retarder comprising a manually operable lever, a crescent-shaped foot attached to the lever and having its horns extending toward the rear of the shoe and away from the fulcrum 35 of the lever whereby pressure applied to the lever acts to retard slipping of the upper more at the sides than at the end of the toe.

13. An end lasting machine having, in combination toe embracing wipers and 40 means for operating them, and a retarder comprising a manually operable lever, a crescent-shaped foot attached to the lever and having its horns extending toward the rear of the shoe and away from the fulcrum 45 of the lever whereby pressure applied to the lever acts to retard slipping of the upper more at the sides than at the end of the toe, said lever having a pin and slot connection with its fulcrum permitting it to accompany 50 the wipers in their advancing movement over the end of the toe.

In testimony whereof I have signed my name to this specification in the presence of two subscribing witnesses.

DAVID L. WINEBERG.
